UNITED STATES PATENT OFFICE.

STANLEY M. BREHM, OF MIAMISBURG, OHIO.

TELEPHONE ATTACHMENT.

1,035,682.

Specification of Letters Patent. Patented Aug. 13, 1912.

Application filed May 17, 1911. Serial No. 627,731.

To all whom it may concern:

Be it known that I, STANLEY M. BREHM, a citizen of the United States, residing at Miamisburg, in the county of Montgomery and State of Ohio, have invented certain new and useful Improvements in Telephone Attachments; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to certain specific improvements in attachments for desk telephones adapted to support a memorandum tablet or the like.

20 The object of the invention is to provide a device of the above type which is simple and inexpensive in construction and which possesses the particular features hereinafter set forth in the specification and specifically named in the claim.

25 In the accompanying drawings, Figure 1 is an elevation of a desk or table telephone instrument having my improved writing tablet support attached thereto. Fig. 2 is a top plan view of the writing tablet support, the post of the telephone instrument appearing in section. Fig. 3 is a bottom plan view of a portion of the table or plate showing the mounting of the spring clip and pencil holder.

30 Describing briefly the well known parts comprising the telephone instrument, 1 designates the base, 2 the standard and 3 the receiver.

In the preferred form of my attachment, 35 I provide a frame 4 consisting of a suitable rod or gage of wire and impose upon it the double purpose of holding the writing table or plate 5 and providing a hinge 6 for the movable member 7 of the standard clamp to swing upon in attaching or detaching the device from the standard 2. The said clamp consists of two members 7 and 8, the latter being fixed and provided with a socket

portion 9 which supports one end 12 of the frame 4, which is turned at a right angle to the plane of said frame. The hinged clamp member 7 has also a socket portion into which a similarly turned end 13 of the frame 4 extends, and thus the hinge 6 is provided. The two clamp members are tightened by a bolt and thumb screw 10-11.

The table-supporting frame 4 is formed of a single strand or rod of suitable wire, and at certain points therein is flattened as at 4', and provided with openings to receive rivets by which the said table is attached to said frame. The ends of said member so constituting the frame are bent at different points where they enter said sockets in order to bring the frame on an incline as shown in Fig. 1, and to thus support the writing table or plate 5 on a suitable incline convenient to the hand of the writer. This makes the forward pivot portion of said frame, or that portion forming the hinge 6, shorter than the other socket portion. At the point where the said frame extends from the side of the table, it is secured to said table by a clip 4 so that the table and frame is one rigid attachment. The upper end of the table 5 is cut out as at 15, and portions of the metal formed into bearings 16 which receive a rod 17 supporting a spring 18. One end of this spring bears against the under side of the table or plate, so while the other end bears against a clip 19 which engages the writing sheets or scratch tablet 20, and holds the same in position on the table at all times. A convenient place for a pencil is provided by stamping from the body of the clip 19, a looped portion 21 which is bent to provide a receptacle for a pencil.

Having described my invention, I claim:

In a device of the type specified, a support comprising two members adapted to encircle a post, one of which is provided with a vertical socket and a hinge element, the other member being provided with a hinge element coöperating with the first named hinge element, means for binding said mem-

bers to the post, a writing table, a supporting frame for said table, said frame terminating in parallel extensions with down turned ends, one of which enters the vertical socket and the other of which passes through the hinge element to form a pintle for the hinge, substantially as specified.

In testimony whereof I affix my signature in presence of two witnesses.

STANLEY M. BREHM.

Witnesses:

R. J. McCARTY,
MATTHEW SIEBLER.
